(57) **CLAIM**

We claim the ornamental design for a loudspeaker, as shown and described.

DESCRIPTION

FIG. 1 is a perspective view of a loudspeaker of a first embodiment according to the present invention;

FIG. 2 is a left side view thereof;

FIG. 3 is a right side view thereof;

FIG. 4 is a front view thereof;

FIG. 5 is a rear view thereof;

FIG. 6 is a top view thereof; and

FIG. 7 is a bottom view thereof.

FIG. 8 is a perspective view of a loudspeaker of a second embodiment according to the present invention;

FIG. 9 is a left side view thereof;

FIG. 10 is a right side view thereof;

FIG. 11 is a front view thereof;

FIG. 12 is a rear view thereof;

FIG. 13 is a top view thereof; and,

FIG. 14 is a bottom view thereof.

The dashed lines illustrate portions of the loudspeaker that form no part of the claimed design. The dash-dot lines define the bounds of the claimed design and form no part thereof.

1 Claim, 14 Drawing Sheets
